UNITED STATES PATENT OFFICE.

ALBERT M. PIGEON, OF PHILADELPHIA, PENNSYLVANIA, ASSIGNOR TO PIGEON
MACHINE COMPANY, OF PHILADELPHIA, PENNSYLVANIA, A CORPORATION
OF PENNSYLVANIA.

CIRCULAR-KNITTING MACHINE.

1,266,045.

Specification of Letters Patent.

Patented May 14, 1918.

Application filed October 25, 1912. Serial No. 727,702.

To all whom it may concern:

Be it known that I, ALBERT M. PIGEON, of Philadelphia, in the county of Philadelphia and State of Pennsylvania, have invented certain new and useful Improvements in Circular-Knitting Machines, whereof the following is a specification, reference being had to the accompanying drawings.

The invention relates more particularly to the mechanism for depressing the spring beard of a knitting needle, whereby the loops of yarn are shed therefrom.

An object of the invention is to provide a beard depressor for each needle, which is so constructed as to move with the cylinder and also to move independently thereof in a direction radially of the cylinder for closing the beard of the needle.

A further object of the invention is to provide a beard depressor for each needle, which is so constructed that it may be rocked into engagement with the needle by stationary or fixed cams during the motion of the needle cylinder.

These and other objects will in part be obvious, and will in part be hereinafter more fully disclosed.

In the drawings, which show by way of illustration one embodiment of the invention, Figure I, is a partial vertical section from front to rear of a knitting machine conveniently embodying my invention.

Fig. II, is a plan partial view of the machine showing the cams for operating the depressors.

Fig. III, is an enlarged detail in vertical section, on line III, III, of Fig. II, showing my improved beard depressor and one of the cams for operating the same.

Fig. IV, is a perspective view on an enlarged scale, of one of the beard depressors removed from the machine.

Fig. V, is a fragmentary plan showing the beard depressor removed from engagement with the beard of the needle and the yarn supporters at each side of the beard depressor.

In the present embodiment of the invention, the knitting machine consists generally in a needle cylinder which is formed with radial ribs providing channels for spring beard needles. These needles are raised and lowered by the usual knitting cams. The invention consists primarily in providing a

beard depressor for closing the spring beard of the needle, in order that the yarn loops on the needle shank may be shed over the same. I have provided a beard depressor for each needle, and said beard depressor is mounted in the channel formed for the needle, and is so constructed that it rocks laterally into engagement with the beard of the needle at the proper time. A stationary cam is carried by the supporting plate at the head of the cylinder, for rocking the beard depressor into engagement with the needle, while a suitable spring or other yielding means mounted on the cylinder, automatically withdraws the beard depressor from engagement with the needle when released by the stationary cams.

Referring more in detail to the drawings, the invention consists of a needle cylinder 1, which is formed with spaced ribs 2, forming needle channels, in each of which is mounted a spring beard needle 3. This spring beard needle is attached, as herein shown, to a needle jack 4, having a butt 5, adapted to be engaged by suitable knitting cams.

The needle cylinder 1, is attached to a gear 6, at the lower end thereof, and said gear rests on a supporting bracket 7, which may be raised and lowered for raising and lowering the needle cylinder to fashion the stocking. The gear 6, meshes with a gear 8, which is mounted to rotate on the main frame 9. The gear 8, is either rotated for rotating the needle cylinder, or oscillated for causing the needle cylinder to oscillate.

Mounted in the upper end of the needle cylinder is a supporting ring 10, on which are carried a plurality of yarn supporters 11. These yarn supporters extend radially of the cylinder and are moved longitudinally by a fixed cam mounted on the supporting ring 10, which is held from rotation relative to the cylinder. The yarn supporters 11, are provided with tapered inner ends 13, which extend between the needles. The yarn which is fed to the needles from a suitable yarn guide 14, is laid on said yarn supporters, and these yarn supporters are gradually withdrawn after the yarn is forced above the beard of the needle, so as to allow the needles to draw the yarn down to form the loops, and to shed the previously formed loops from the shank of the needle. These yarn supporters are also pro-

vided with a radial extension 15, which serves as a support for the knitted web.

This combined fabric or web and yarn supporter forms no part of the present invention, but is shown, described and claimed 5 in my co-pending application Serial No. 633,938, filed June 19th, 1911.

The spring beards of the needles are closed for shedding the previously formed 10 loops of yarn thereon by beard depressors 16. There is a beard depressor for each needle, and said beard depressor is located in the needle channel formed in the cylinder, and rotates with the cylinder. A description of one of these beard depressors 15 will answer for all. Each beard depressor is formed on its inner face with a high point 17. Said beard depressor is cut away at 18, above said high point, and is 20 tapered as at 19, below said high point. This sharing of the beard depressor allows said beard depressor to rock about said high point as a fulcrum, and in a direction radially of the cylinder. Said beard depressor 25 is held in the needle cylinder by a coiled spring 20, which lies in a notch 21, formed in the ribs of the needle cylinder, and engages a V-shaped notch 22, formed in the lower end of each beard depressor. 30 The extreme lower end 23, of the beard depressor is tapered to a point, so that said beard depressor may be readily inserted in the needle channel without disturbing any of the other beard depressors or any of the 35 parts of the knitting machine.

When the lower end of the beard depressor reaches the coiled spring 20, it will be forced outward, so that said spring will slide into the V-shaped notch in the lower 40 end of the beard depressor. This notch being V-shaped, the beard depressor may be readily removed by pulling the same from the upper end thereof, and may be readily replaced merely by forcing said beard depressor 45 into its proper position.

The upper end of the beard depressor extends between the yarn-supporting members 11, and is formed with a pressing face 24, and a tapered upper end at 25. This tapered upper end 25, forms a trough with the needles, into which the yarn is laid as it is fed to the needles. The upper end of the beard depressor is slightly widened, so as to substantially fill the space between adjacent 50 yarn supporters. This insures the beard depressor engaging the spring beard of the needle without any liability of said needle slipping off the pressing face of said beard depressor.

60 The coiled spring 20, bearing on the lower ends of the beard depressors, forces said lower ends inwardly toward the cylinder, causing the beard depressors to rock about the high point thereof. This movement of 65 the beard depressors withdraws the pressing

face thereof from the spring beard needle. This is the normal position of the beard depressors.

Mounted on the fixed plate at the upper end of the cylinder, are two cams 27, and 70 28. These cams are located at opposite sides of the knitting point. Said cams engage the upper ends of the beard depressors as they pass by the same. As the cam engages the beard depressor, it will be forced 75 inwardly at its upper end, so as to bring said beard depressor into engagement with the spring beard of the needle to close the same. As soon as the beard depressor passes the cam, it will be automatically withdrawn 80 from engagement with the beard of the needle. One of the cams operates to press the beards of the needles when the cylinder is moved in one direction for releasing the yarn loop around the shank of the needle, 85 while the other cam operates for depressing the beards of the needles when the cylinder is moving in the other direction.

It will be noted from the above description, that I have provided a spring beard 90 depressor which is extremely simple in construction and operation. These beard depressors may be readily removed and replaced, and in view of the fact that only a slight rocking movement is given to the 95 beard depressor, very little wear occurs either on the beard depressor or the needle cylinder which supports the same.

It is obvious that minor changes in the details of construction and arrangement of 100 parts may be made, without departing from the spirit of the invention, as set forth in the appended claims.

Having thus described my invention, I 105 claim:

1. The combination in a knitting machine of spring beard needles, a needle cylinder provided with channels in which the needles slide; individual beard depressors disposed within the needle channels and constructed 110 so as to rock therein; means for rocking the beard depressors in succession to close the needle beards, each beard depressor having its extent radial to the cylinder wholly inclosed within said needle channels, whereby 115 said beard depressors may be moved lengthwise of the needle channels for removal or insertion without disturbing any of the other beard depressors or any of the parts of the machine.

2. The combination in a knitting machine of spring beard needles, a needle cylinder provided with channels in which the needles slide; individual beard depressors disposed 125 within the needle channels and mounted to rock in said channels to close the needle beards; means for rocking the beard depressors including a cam and spring means, said beard depressors having their extent radial to the cylinder wholly inclosed within 130

- said needle channels, whereby said beard depressors may be moved lengthwise of the needle channels for removal or insertion without disturbing any of the other beard depressors or any of the parts of the machine, said spring means yielding to permit the removal of the beard depressors and the insertion of the same in the machine.
3. In a knitting machine, the combination of a needle cylinder, a series of spring beard needles carried thereby, yarn supporters adapted to extend between the needles, a beard depressor for each needle located between the yarn supporters and having a widened needle-engaging face adapted to fill the space between the yarn supporters, and means for rocking said beard depressors radially of the cylinder for moving the same into and out of engagement with the needles.
4. In a knitting machine, the combination of a needle cylinder having a series of needle channels formed therein, a series of spring beard needles mounted in said channels, a beard depressor in each channel and extending substantially parallel with the needle depressor having a high point on which said depressor may rock, means for engaging the upper ends of the beard depressors for rocking the same into engagement with the needles, and a coiled spring for engaging the lower ends of the beard depressors for rocking the same out of engagement with the needles.
5. In a knitting machine, the combination of a needle cylinder having a series of needle channels formed therein, a series of spring beard needles mounted in said channels, a beard depressor in each channel and extending substantially parallel with the needle depressor having a high point on which said depressor may rock, means for engaging the upper ends of the beard depressors for rocking the same into engagement with the needles, and a coiled spring for engaging the lower ends of the beard depressors for rocking the same out of engagement with the needles.
6. In a knitting machine, the combination of a needle cylinder having a series of needle channels formed therein, a series of spring beard needles mounted in said channels, a beard depressor in each channel and extending substantially parallel with the needle depressor having a high point on which said depressor may rock, means for engaging the upper ends of the beard depressors for rocking the same into engagement with the needles, and a coiled spring for engaging the lower ends of the beard depressors for rocking the same out of engagement with the needles, said beard depressors and said needle cylinder having registering grooves formed therein in which said coiled spring rests.
7. In a knitting machine, the combination of a needle cylinder having a series of needle channels formed therein, a series of spring beard needles mounted in said channels, a beard depressor in each channel, the inner face of said beard depressor having a high point on which said depressor may rock, means for engaging the upper ends of the beard depressors for rocking the same into engagement with the needles, and a coiled spring for engaging the lower ends of the beard depressors for rocking the same out of engagement with the needles, said beard depressors and said needle cylinder having registering grooves formed therein in which said coiled spring rests, the groove in the beard depressor being V-shaped, whereby said beard depressors may be withdrawn, and the lower end of each beard depressor being tapered, whereby the same may be readily inserted beneath the coiled spring.
- In testimony whereof, I have hereunto signed my name at Philadelphia, Pennsylvania, this twenty-first day of October, 1912.

ALBERT M. PIGEON.
